Attorney.

UNITED STATES PATENT OFFICE.

CHARLES H. WAGNER, OF PENBROOK, PENNSYLVANIA.

NUT-LOCK.

1,359,299.

Specification of Letters Patent. Patented Nov. 16, 1920.

Application filed August 2, 1919. Serial No. 314,898.

To all whom it may concern:

Be it known that I, CHARLES H. WAGNER, a citizen of the United States, residing at Penbrook, in the county of Dauphin and State of Pennsylvania, have invented certain new and useful Improvements in Nut-Locks, of which the following is a specification.

The object of this invention is to provide 10 an improved nut-lock, so designed as to overcome the objectionable features and excessive cost of manufacture of earlier constructions of such devices, and yet primarily to insure the very maximum degree of efficiency in operating to prevent the removal 15 of a nut from a bolt by accidents, or in any way other than manually by voluntary intent.

A further object of this invention is to 20 provide a device of this character which demands the least possible alteration in the construction of a bolt, to provide for no change whatever in the ordinary construction 25 of a nut, to provide means operative to effect a maximum binding of the nut against the articles being united by the complete bolt, and to provide means for preventing accidental displacement of said last-named means.

And a still further and more specific object is to provide a bolt having a single narrow groove extending longitudinally of the axis of the bolt and across its threads, to provide an ordinary internally threaded 35 nut for said bolt, to provide an internally threaded lock-nut for said bolt, operative to bind against said first nut and provided with spaced grooves extending longitudinally of the axis of said lock-nut and across 40 its threads, and to provide removable means adapted to enter the groove in the bolt longitudinally and any one of the longitudinally extending grooves in said lock-nut, to effect a keying of the lock-nut against revolving with respect to the bolt, said keying means being provided in turn with means to prevent its accidental displacement within or removable from the groove in said bolt.

With these and further objects in view, 50 the present invention comprises details of construction illustrated in the accompanying drawings and fully described herein-after with respect thereto, said drawings comprising Figure 1, which is an elevational view of the preferred embodiment of the invention; Fig. 2, which is an end view of

the bolt, lock-nut, and keying means assembled; Fig. 3, which is a longitudinal partially sectional view of the elements comprising the invention in assembled relation; Fig. 4, which is a collective view of the several elements of the invention in spaced relation with respect to one another and sectioned along their longitudinal axis; and Fig. 5, which is a perspective view of the 65 key member.

Referring to the drawings, an ordinary type of bolt is shown as comprising a shank 1, terminating at one end in a head 2, and at its opposite end provided with external screw-threads 3, which are crossed by a milled groove 4, running preferably along one side only of the bolt and parallel with the longitudinal axis thereof.

Adapted to be screwed upon the threaded portion of this bolt is an ordinary nut 5, provided with a central internally threaded aperture 6. The said nut when screwed upon the bolt as far as desired is bound in position by a specially constructed lock-nut 7.

The said lock-nut is provided with a central longitudinally extending internally threaded aperture 8, the threads of said aperture, however, being crossed by a plurality of relatively slightly spaced longitudinally extending grooves 9. These grooves preferably occur sufficiently close together to make it possible for one of them to be readily brought into a position registering with the groove 4 in the bolt 1.

After the first nut and lock-nut have been assembled upon the said bolt in the desired position, a small inexpensively made key is used to prevent the accidental displacement of the lock-nut, which would thereby release the primary nut of the bolt. This key preferably comprises a quadri-laterally shaped section 10 of metal relatively soft when compared with the steel or iron used in the bolt and nut construction, said section being normally positioned so that one of its angular portions extends into the groove 4 of the bolt, while the oppositely positioned angular portion extends into the groove 9 of the lock-nut 7 in registry with the 105 groove 4.

After this condition has been effected, the oppositely extending wings 11 of the key are bent or forced downwardly into the threads of the bolt, thus, without mutilating the bolt-threads, preventing the key from displacement within and the accidental re-

moval from the registering grooves above described.

The key is illustrated in detail in Fig. 5. The same embodies laterally extending wires 12 which are secured to the wings 11 and may be made to encircle the bolt and engage the threads thereof, after which the free ends of the wires may be twisted to prevent free accidental disengagement from the said threads, and probably even more positively preventing the accidental displacement of the key member.

Having thus described my invention, what I claim and desire to protect by Letters Patent of the United States is:—

A bolt having a head and its opposite end threaded and a longitudinal groove in the threaded end, a nut having a threaded open-

ing to receive the threaded end of the bolt, a lock-nut having a threaded opening to receive the said threaded end and having spaced longitudinal grooves extending through its threaded portion, a key for insertion within the grooves of the bolt and nut-lock, wings carried by the outer end of the key, and extending laterally beyond the same for substantial distances, said wings being longitudinally curved to conform to the curvature of the threads of the bolt, and wires secured to the wings and adapted to encircle the bolt and to be secured together to prevent accidental displacement of said key.

In testimony whereof I have affixed my signature.

CHARLES H. WAGNER.
